UNITED STATES PATENT OFFICE

163,234

COMBINED RADIO, PHONOGRAPH, AND TABLE

John W. Wilson, Chicago, Ill., assignor to Lincoln National Furniture Company, Chicago, Ill.

Application March 8, 1950, Serial No. 8,391

Term of patent 7 years

(Cl. D56—4)

To all whom it may concern:

Be it known that I, John W. Wilson, a citizen of the United States, and resident of Chicago, in the county of Cook and State of Illinois, have invented a new, original, and ornamental Design for a Combined Radio, Phonograph, and Table, of which the following is a specification, reference being had to the accompanying drawings, forming a part thereof:

Fig. 1 is a perspective view of a combined radio, phonograph and table showing my new design;

Fig. 2 is a top plan view of the same;

Fig. 3 is an enlarged fragmentary sectional view taken on the plane of line 3—3 of Fig. 2; and

Fig. 4 is an enlarged fragmentary sectional view thereof, taken on the plane of line 4—4 of Fig. 2.

I claim:

The ornamental design for a combined radio, phonograph, and table, substantially as shown.

JOHN W. WILSON.
